CLAIM

The ornamental design for a solar energy lawn lamp as shown and described.

DESCRIPTION

FIG. 1 is a front, right, top perspective view of a solar energy lawn lamp showing my new design;

FIG. 2 is a back, left, top perspective view thereof;

FIG. 3 is a front view thereof;

FIG. 4 is a back view thereof;

FIG. 5 is a left view thereof;

FIG. 6 is a right view thereof;

FIG. 7 is an enlarged top view thereof;

FIG. 8 is an enlarged bottom view thereof;

FIG. 9 is an enlarged view of the encircled area 9 of FIG. 1;

FIG. 10 is an enlarged view of the encircled area 10 of FIG. 1;

FIG. 11 is an enlarged view of the encircled area 11 of FIG. 2;

FIG. 12 is an enlarged view of the encircled area 12 of FIG. 3;

FIG. 13 is an enlarged view of the encircled area 13 of FIG. 4;

FIG. 14 is an enlarged view of the encircled area 14 of FIG. 4;

FIG. 15 is an enlarged view of the encircled area 15 of FIG. 5; and,

FIG. 16 is an enlarged view of the encircled area 16 of FIG. 5.

The broken lines shown on the drawings depict portions of the solar energy lawn lamp that form no part of the claimed design. In FIGS. 1-5 and 9-16, the broken lines encircling portions of the solar energy lawn lamp depict the enlarged view boundaries that do not form part of the claimed design.

1 Claim, 16 Drawing Sheets
